UNITED STATES PATENT OFFICE

2,583,865

BATHING SUIT

Evelyn McIlhinney, Ottawa, Ontario, Canada

Application August 25, 1948, Serial No. 46,130

14 Claims. (Cl. 2—67)

1

My present invention relates to certain new and useful improvements in a bathing suit.

An object of the invention is to provide a bathing suit that will afford the wearer considerable support especially in the areas of the bust and abdomen.

A further object of the invention is to provide a bathing suit of novel construction to allow for adjustable uplift of the breasts, and circumferential tensioning of the abdominal support and at least a part equalizing of the latter tensioning drawing upwards on the crotch strap to hold it snugly.

A further object of the invention is to provide a back-lacing bathing suit wherein the upper portion consists of a tailored brassière structure from which both the combined abdominal supporting panel and crotch strap and outer cover or skirt are suspended, and in which the back-lacing besides closing the outer cover of the garment about the wearer also tightens the circumferential tensioning of the abdominal supporting panel and draws up at least slightly in an equalizing action on the crotch strap to hold it in snug, close-fitting engagement.

A further object of the invention is the provision of a woman's bathing suit of stylish design allowing maximum exposure while yet providing freedom and comfort, unusual support and modest coverage.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 and 1A are front and back perspective elevations of this bathing suit;

Figures 2 and 3 are enlarged vertical and horizontal transverse sections thereof;

Figure 4 is a detail of the open, back-lacing structure; and

Figure 5 is a perspective elevation of a modified brief form of the garment.

Possessing the styling of a "skimpy," dressmaker model garment, this bathing suit may be considered structurally as consisting of three sections, viz., the bust-covering, body-encircling, up-

per portion or brassière A, the U-shaped abdominal support and stress-equalizing crotch unit B suspended therefrom, and the form-fitting outer cover C that depends from the brassière A, substantially free and independent of the vertical U crotch traverse.

The instant form shown in Figures 1—4 inclusive, is seen to possess a tailored brassière top A, having spaced breast cups 1 mounted on the upper edge, one on either side of the front median, of a body-encircling band 2, the connectible free ends 3 of which are in normally spaced relation at the back. Shoulder straps 4 extend from the top of each cup to the band 3 at the back. Suspended from this brassière body-encircling band 2 is the U-shaped unit B, consisting of a strong though stretchable abdominal supporting panel 5, a non-stretchable crotch strap 6 and an upwardly extending rear extension 7. The panel 5 is connected along its upper free end to the brassière body-encircling band 2 and at its lower end, on a V-shaped bias line to the non-stretchable crotch strap 6 that tapers in width to traverse the crotch and connects in turn on a V-shaped bias line with the extension 7 that continues up to join the confronting ends 3 at the back of the band 2, being bifurcated for a substantial part of its length to provide a deep open-back slit 8 reaching down below the waist-line to a level substantially even with the bottom of the panel 5. Preferably the crotch traversing strap 6 and the extension 7 are of the same material as the bra's top A and outer covering portion C but with the crotch strap having the right side of the material outermost and the extension with the material reversed for a purpose to be later set forth.

The foregoing is the basic or skeleton structure of my bathing suit with which various forms of trunk enveloping covers may be used. In the preferred embodiment loose pantie sections 10 hang from the brassière band 2 on each side of the U-shaped unit B and are joined thereto down opposite sides and finished with elastic 11 around the leg-defining openings 12 at the bottom.

The skirt-like, form-fitting outer covering C depends from the brassière band 2, being connected thereto all around and is slit down the center of the back in registry with the slit 8 in the crotch strap extension 7 and attached to the said extension along the edges of the slit 8 so that the reversed material of the extension now appears as a finished facing therefor. At the front of the garment, the covering C is stitched to the opposite vertical edges of the abdominal

supporting panel 5, the panel-superposing area of the outer cover C being first gathered or given some transverse or horizontal slack and if desired the vertically extending laterally spaced rows of stitching 14 may be carried down to include the crotch strap 6 to at least the level of the bottom point of the V-shaped bias joint. Similarly the stitching connecting the back of the cover with the bifurcated crotch strap extension 7 may be continued down to the level of the connection of the crotch strap 6 therewith so that the skirted outer cover C may not float up above the limits of the crotch strap at front or rear to expose any other than right-side-out material. Opposite sides of the deep, open-back slit 8 are provided with spaced eyelets 15 for a gap-closing, tension adjusting draw lace 16 and even the shoulder straps 4 include one or more such eyelets and are included in the lacing.

Thus it will be seen that when the garment is adjusted on the wearer and the draw lace 16 tightened, the closing of the open-back gap or slit 8 pulls in the outer cover C over the wearer's waist to whittle the dimension thereof yet the stress at the front does not cause the abdomen to protrude as the underlying supporting panel 5 tightens transversely to flatten the abdomen without disclosing any of the strain thereof on the overlying, previously gathered portion of the cover C. Simultaneously the transverse stretching of the panel 5 tends to shorten the same a little vertically with the resultant drawing up of the crotch strap 6 into a comfortably snug and modestly concealing fit. Additionally the tightening of the draw lace 6 when it connects the shoulder straps 4 raises the breasts and draws in the brassière to engage closely along the edges.

In the modified, half-skirted style seen in Figure 5, the crotch strap extension 7' assumes the form of a diamond-shaped seat expansion section fitting as a gusset into the bottom back of the outer cover C'. Furthermore the pantie side sections 10 are dispensed with in this briefer model but substantially the same waist-slimming, abdomen-flattening and crotch strap snugging action follows the tightening of the gap-closing draw lace in the open-back slit reaching down to below waistline level.

From the foregoing description taken in connection with the accompanying drawings, it will be manifest that a bathing suit is provided that will fulfil all the necessary requirements of such a garment, but as many changes could be made in the above description and many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

Having thus described the invention, what I claim as new and desire to secure by Letters Patent is:

1. A bathing suit comprising a body-encircling band to lie just below the bust, a pair of breast cups mounted thereon, a U-shaped abdominal panel and crotch structure suspended from said band and an outer cover lower portion depending also from said body-encircling band; the abdominal panel of said U-shaped structure being of strong stretchable material.

2. A bathing suit comprising a body-encircling band to lie just under the bust, a bust-supporting brassière mounted thereon, a substantially

U-shaped abdominal support and crotch strap unit suspended from said brassière band and a trunk-enveloping outer cover depending also from said brassière band and overlying said U-shaped abdominal support and crotch strap unit.

5 3. The combination with the structure set forth in claim 1 wherein the bathing suit outer cover is open down the back from and including the body-encircling band and provided with an adjustable draw-string threaded through opposite sides of said back opening for drawing the sides thereof together with the desired tension.

10 4. A bathing suit having a cover reaching from above the breasts to the crotch and having an open slit reaching down the back to a point below the waistline, an adjustable tension gap-closing means therefor, and an abdominal-flattening panel stitched along its opposite vertical edges to the inside of said bathing suit cover at the front with the superposing portion of the bathing suit gathered transversely between said spaced panel-attaching rows of stitching and subject to the adjustable tension of said gap-closing means.

15 5. The combination with the structure set forth in claim 2 wherein said U-shaped unit comprises a stretchable abdominal support panel and a non-stretchable crotch strap.

20 6. The combination with the structure set forth in claim 2 wherein said U-shaped unit is connected to the brassière body-encircling band by the top of the abdominal support panel at the front and by an extension of said crotch strap at the rear.

25 7. The combination with the structure set forth in claim 2 wherein said U-shaped unit is connected to said outer cover only part way down opposite sides.

30 8. The combination with the structure set forth in claim 2 wherein said U-shaped unit is connected to said outer cover down opposite sides of the abdominal support panel and continuing also part way only down the sides of said crotch strap.

35 9. A back-lacing bathing suit comprising a bust-supporting brassière mounted on a body-encircling band whose ends are in normally spaced relation at the back, a substantially U-shaped unit consisting of an abdominal supporting panel, crotch strap and strap extension connecting by opposite ends to the body-encircling band of said brassière; a trunk enveloping outer cover depending also from said brassière band and being open down the back to approximately the level of the bottom of said panel; and an adjustable draw lace for closing the back of said band and cover; said U-shaped unit being attached to said outer cover by a row of stitching down opposite edges of said abdominal supporting panel and terminating well above the lower edge of said cover and between which rows of stitching said outer cover is transversely gathered so that the strain of back lacing is impressed on the underlying panel and not on that portion of the outer covering in the area of the abdomen.

40 10. The combination with the structure set forth in claim 9 wherein the crotch strap of the U-shaped unit is composed of the same material as the outer cover and with the right-side out while the strap extension has the material reversed, the rows of stitching joining said U-shaped unit and outer cover reaching to at least the lowest level of the V-shaped bias line at the juncture of said strap and panel and said

crotch traversing strap adjoins both the panel and extension on V-shaped bias lines.

11. The combination with the structure set forth in claim 2 of loose pantie side sections suspended also from the body-encircling band of the brassière and attached down opposite edges to the U-shaped unit but otherwise free from said outer cover and finished with elastic edging around leg defining openings at the bottom.

12. The combination with the structure set forth in claim 4 wherein a crotch traversing strap extends from the lower edge of said panel.

13. The combination with the structure set forth in claim 2 wherein said crotch strap has a substantially diamond shaped extension fitting as a gusset at the back into the cover of the bathing suit proper.

14. The combination with the structure set forth in claim 1 wherein the bathing suit has an open slit down the back and the bust covering upper portion has shoulder straps, of an adjust-

able gap-closing draw lace therefor threaded through eyelets in opposite sides of said slit and in said shoulder straps respectively.

EVELYN McILHINNEY.
